UNITED STATES PATENT OFFICE

WARREN FUHRMANN, OF WESTFIELD, NEW JERSEY

CLOTHESLINE CONTROL

Application filed May 22, 1930. Serial No. 454,594.

This invention pertains to improvements in clothes line supports, particularly to the arrangement as mounted on a window frame, and serves to have the clothes line brought into the room through an open window, when desired to apply and remove the articles; and which can thereupon be swung outwardly to permit closing of the window, yet will not disturb the usual tension on the line.

One of the objects of the invention is to provide a device of this character that can be readily and strongly formed out of sheet metal by simple cutting and bending, yet will form a rigid construction and properly support the moving parts; and which will strongly and securely hold the main lever in the two positions for use.

A further object of the invention is to provide a member that will automatically serve to lock the rope against displacement from the guide pulley from which it is detached at the inner position, when the arm is swung to move the parts to the outer position.

In the accompanying drawings showing one embodiment of my invention

Figure 1 is a perspective view of the structure applied to a window frame and placed in the inner position.

Fig. 2 is a side elevation of the device.

Fig. 3 is a plan view.

Fig. 4 is a partial side elevation with the lever lowered.

Fig. 5 shows the lever detached.

Fig. 6 shows the supporting bracket.

Fig. 7 shows the locking pin.

Fig. 8 shows the main frame, with adjacent parts.

As shown in the drawings, the device consists essentially of a main frame 2, a lever member 3, and a hanger bracket 4. The frame is shown in the form of a plate or strip of sheet metal with bent ears 5 and 6 at the ends that are apertured for pivots whereby it can swing on ears 7 and 8 on the supporting bracket 4. The latter ears have slots 9 and 10, for adjustment bolts 11 and 12 mounted in holes in the ears 5 and 6. This bracket has bent lugs 13 and 14, and also lugs 15 and 16 for mounting the bracket on the window frame 17.

The supporting plate 2 is shown provided with an arm 18 having a perforated ear 19 at its outer end; and the plate 2 has an apertured ear 20 near the arm that registers with said ear 19, to receive a shaft 21 extending across the arm. A pulley 22 is mounted at the middle of this shaft and extends into the slot 23 of the arm, and other ears 24 and 25 on the arm 18 have holes that engage the shaft adjacent the pulley. A brace in the form of a curved arm 26 extends from the outer end of the arm over to the plate to prevent lateral bending of the arm from pressure of the rope on the pulley.

This shaft 21 also serves to form a bearing for the swinging lever, that is shown composed of two bars 27 and 28 connected at the outer end by a handle 29, and which receive a pulley 30 between the bars at this end. At the other ends of the bars they are separated a greater distance apart, and apertured to swing on the shaft 21 adjacent its end supports in the arm. The arm or lever thus swings concentric with the pulley 22, and the pulleys 30 and 22 remain the same distance apart in all positions of the lever.

Means are arranged to secure the lever in the horizontal position, in which it will extend inwardly through the window, with the bracket and arm mounted on the outer portion of the frame, as shown in Fig. 3. A curved bar 31 is secured to the lever at one end, and is formed concentric with this lever. A spring pin 32 is mounted on an extension 33 of the frame, and will engage the apertured portion 34 of the bar 31 when the arm projects inwardly to lock the lever in this position; and when the lever is lowered the lock pin will engage another apertured portion 35 of the bar to hold the lever in such position.

The frame member 2 is further provided with an arm 36 projecting outwardly with a pair of spaced apertured ears, 37-38, between which is pivoted a pulley 39, that is in the same plane as the two pulleys 22 and 30.

In the use of this device the endless rope 40 is brought in over the pulley 22, and passed around the pulley 30 on the inner free end of the lever, shown in Fig. 1 projecting

into the room. The rope then passes outwardly and of course is passed around a suitable pulley at a distant location in the usual manner. The lower portion of the pulley will sag down a short distance below the framework, and can have the articles applied thereto and then the rope at this portion moved outwardly until the desired number of articles are hung, or the capacity reached. 5 It will be understood that no articles are to be applied inside of the frame in the final position, and this portion 41 of the rope is then raised and caused to engage the third pulley 39, as indicated in Fig. 1, that will 10 support the two portions of the rope in proximity. The lever 3 can now be released by the locking pin 32, and is swung downwardly to the upright position as indicated in Fig. 4, and will thus be entirely outside of the 15 window to permit the sash to be closed. During this operation the lower rope portion 41 will be supported by the pulley 39 on the frame, while the portion around the pulley 30 on the lever will move downwardly, and 20 of course the other portion of the rope will still engage the pulley 32 at the axis of the lever. This will cause the rope to retain its tension because the pulley 30 remains at the same distance from the pulley 22, and the 25 other pulley 39 is placed close to the pulley 22. But the rope is liable to be displaced from the small pulley 39, therefore a guard plate 42 is mounted on the lever 3 that in this upright position will be brought close to 30 the pulley 39 and the rope cannot escape its bearing on this pulley.

It will be seen that a structure of this character is very easily made from sheet metal by cutting and bending dies, and can 35 be quickly formed and assembled; and also that it possesses the requisite strength and rigidity, yet is not bulky and does not interfere with the proper use of the window.

What I claim is:—

- 45 1. A frame consisting of a strip of sheet metal having supporting ears at the top and bottom, an arm extending out from the strip at the top in its plane with an apertured ear at its end, an apertured ear on the strip alined with the said first ear, a shaft turning in said ears, a pair of ears at the intermediate part of said arm that engage said shaft, a pulley on the shaft between said latter ears, a lever having apertured spaced bars 50 which at one end engage said shaft forming a pivot about which to swing the lever, a pulley on the free end of the lever alined with said first pulley, a second arm extending from said plate, a guide pulley on said latter arm in the same plane with said first and second pulleys, and means for locking the lever in upright and horizontal positions.
- 55 2. A frame consisting of a strip of sheet metal having supporting ears at the top and bottom, an arm extending out from the strip at the top in its plane with an apertured ear at its end, an apertured ear on the strip alined with the said first ear, a shaft turning 60

at the top in its plane with an apertured ear at its end, an apertured ear on the strip alined with the said first ear, a shaft turning in said ears, a pair of ears at the intermediate part of said arm that engage said shaft, a pulley on the shaft between said latter ears, a lever having apertured spaced bars which at one end engage said shaft forming a pivot about which to swing the lever, a pulley on the free end of the lever alined with said first pulley, a second arm extending from said plate, a guide pulley on said latter arm in the same plane with said first and second pulleys, means for locking the lever in upright and horizontal positions, and a guard plate on the lever that is brought close to said guide pulley when the lever is in upright position to prevent escape of the rope from the pulley.

3. A frame consisting of a strip of sheet metal having supporting ears at the top and bottom, an arm extending out at the top of the strip with an apertured ear in its end, an apertured ear on the strip alined with the said first ear, a shaft turning in said ears, a pair of ears at the intermediate part of said arm that engage said shaft, a pulley on the shaft between said latter ears, said arm forming a guard for the rope on the pulley, a lever having apertured spaced bars which at one end engage said shaft forming a pivot about which to swing the lever, a pulley on the free end of the lever alined with said first pulley, a second arm extending from said plate, a guide pulley on said latter arm in the same plane with said first and second pulleys, and means for locking the lever in upright and horizontal positions.

4. A frame consisting of a strip of sheet metal having supporting ears at the top and bottom, a bracket plate having ears at the ends that engage said ears and lateral ears to engage the window frame, an arm extending out from the strip at the top of its plane with an apertured ear at its end, an apertured ear on the strip alined with the said first ear, a shaft turning in said latter ears, a pair of ears at the intermediate part of said arm that engage said shaft, a pulley on the shaft between said latter ears, a lever having apertured spaced bars which at one end engage said shaft forming a pivot about which to swing the lever, a pulley on the free end of the lever alined with said first pulley, a second arm extending from said plate, a guide pulley on said latter arm in the same plane with said first and second pulleys, and means for locking the lever in upright and horizontal positions.

5. A frame consisting of a strip of sheet metal having supporting ears at the top and bottom, an arm extending out from the strip at the top in its plane with an apertured ear at its end, an apertured ear on the strip alined with the said first ear, a shaft turning 125

in said ears, a pair of ears at the intermediate part of said arm that engage said shaft, a pulley on the shaft between said latter ears, a bridge piece extending across the frame 5 over the said pulley from and between the bases of said ears, a lever having apertured spaced bars which at one end engage said shaft forming a pivot about which to swing the lever, a pulley on the free end of 10 the lever alined with said first pulley, a second arm extending from said plate, a guide pulley on said latter arm in the same plane with said first and second pulleys, and means for locking the lever in the upright and in the 15 horizontal positions.

Signed at Newark on this 10th day of May, 1930.

WARREN FUHRMANN.
